COMBINED VALVE LIFTER AND SPRING COMPRESSOR

Joseph Sunnen, Kirkwood, Mo.

Application January 6, 1934, Serial No. 705,502

4 Claims. (Cl. 29—86.3)

My invention has relation to combined valve lifters and spring compressors for use in performing service operations on automobile engines, and it consists in the novel features of construction 5 more fully set forth in the specification and pointed out in the claims.

The invention is more particularly directed to what may be termed the overhead type of spring compressor in that it has its support on top of the 10 motor block while compressing the spring preparatory to removing a valve, and is an improvement over the subject-matter of my co-pending application Serial No. 671,087. Because of the manner in which this type of valve lifter is operated the 15 frame is necessarily formed in the shape of a loop, or C, and is also referred to among mechanics as a C-type lifter.

Because of the wide span between the point of support and the movable seat for compressing the 20 spring this type of lifter heretofore has not been very successful on account of the difficulties of making the frame sufficiently strong without undue cumbrousness and excessive weight. It is the 25 principal object of the present invention to so construct the lifter frame that it will combine strength and rigidity with light weight, and at the same time so arrange the operating parts that the lifter may be actuated with convenience and minimum effort.

In a valve lifter of this type, which is inherently 30 bulky, the arrangement of the parts with a view to convenience and simplicity of operation is of the utmost importance in order that the tool may be practical. It is also an object of the invention to provide means for securely holding the 35 spring while compressing the same, said means readily accommodating itself to springs of various sizes. Another object of the invention is to provide seat members for the spring which, although 40 possessing some flexibility, embody means for limiting the movement of the individual seat members so that the forces to which they are subjected may not permanently distort or strain them. Further and other advantages will be 45 better apparent from a detailed description of the invention in connection with the accompanying drawings, in which:

Figure 1 is a side elevation of my improved 50 valve lifter and spring compressor shown applied to a motor block which is shown in partial section, and progressive positions of the operating parts being shown dotted; Fig. 2 is a view similar to Fig. 1 except that the operating handle of the valve lifter is shown in a series of positions near 55 the end of its throw, and the portion of the frame

receiving the spring seat members is broken away; Fig. 3 is a top plan of my invention; Fig. 4 is a cross-sectional detail taken on the line 4—4 of Fig. 1; Fig. 5 is a plan view of the spring seat members and the end of the frame receiving said members with parts in section; Fig. 6 is a longitudinal sectional detail taken on the line 6—6 of Fig. 5; Fig. 7 is a cross-sectional detail taken on a plane indicated by the line 7—7 of Fig. 6; and Fig. 8 is an enlarged detail showing the inner end 10 of the spring seat members, parts of which are in section.

Referring to the drawings, M represents a motor block, the valve V of which is to be removed. As is well known in the art, the valve V cannot be removed without first disconnecting the valve spring S from the valve stem V', said spring being seated in the valve seat or washer S' held securely to the valve stem V' by the lock L. The function of the valve lifter is to raise 15 the spring sufficiently so that the lock L may be removed and thereby disengage the valve from the spring S whereupon the valve is readily lifted out of place. My improved valve-lifter comprises 20 a frame 1, shaped in the form of the letter C, said frame having a cross-section of a hollow rectangle. The lower end of the frame 1 carries in permanently fixed relation an extension E which comprises a pair of spaced channel arms 2, 2 rigidly 25 secured together by rivets 3, 3 and spacers 4, 4. The outer extremities of the channel arms 2, 2 diverge to form spring seats 5, 5 and, of course, the upper flanges of the channel terminate at 30 points 6, 6 just to the rear of the spring seats 5, 5 so as not to interfere with the reception of the 35 spring S on said seats. The spring seats 5, 5 are adjustable to and from each other (for the purpose of adapting them to various sizes of springs) by means of a screw 7 and nut 8 for receiving the 40 screw, the former passing through an opening o in the side of one arm 2 and the latter passing through an opening o' in the side of the opposite arm 2. When the screw and nut are screwed together the seat members are drawn inwardly and when the screw and nut are screwed apart the 45 seat members are, of course, allowed to separate. A tongue 9 serving the purpose of an abutment is fixed between channel arms 2, 2 and spot-welded at points 10, 10 near the inner end of 50 said arms, said tongue extending outwardly to a point about midway between the seats 5, 5 and the end of the frame 1. It will be observed (Figs. 5 and 8) that the arms 2, 2 diverge slightly so that the sides thereof have a gradually increasing 55 clearance with the tongue toward the outer end 55

thereof. The purpose of this space is to permit of a certain amount of resiliency in the individual arms 2, 2, but to limit this resiliency so that the arms 2, 2 cannot be bent beyond their elastic limit and thus permanently distorted. Openings 11, 11 are provided in the top and bottom walls of the upper horizontal part 1' of the frame 1 and a tubular bearing 12 is securely fixed into said openings, said bearing being of substantial length and having its longitudinal axis coincident with the center point between the seats 5, 5 so that when the valve lifter is applied to the spring S and the frame, held so that the upper portion 1' is in a horizontal position, the tubular bearing 12 will be directly in line with the valve V. The importance of the alinement of these parts will be apparent from what follows.

A square threaded screw 13 is slidably mounted in the bearing 12 and has a handle 14 fixed to its upper end, said handle having spaced lugs 15, 15 on its under surface 16, either one of which (there being two for convenience) may cooperate with the frame 1 in holding a spring S when it is to be compressed preparatory to being replaced on the valve stem. The screw 13 carries a block 17 on its threaded portion, said block being internally threaded to fit the threads of the screw 13, whereby the position of the block on the screw may be adjusted by rotating the screw in its bearing sleeve 12 so that it may be either advanced through or withdrawn from the block 17.

A bell-crank lever 18 formed of similar spaced components 19, 19 is mounted on a pin 20 adjacent to a tubular bearing 12, said pin traversing the sides of the horizontal part 1' of the frame 1 and spaced therefrom by means of a spacing washer 21. One arm 22 of said bell-crank lever projects laterally forward and the other arm 23 projects downwardly, the forward arm 22 being connected by a link 24 to an ear 25 extending from the side of the block 17. A handle lever 26 is pivotally mounted at its inner end on a pin 27 traversing the horizontal part 1' of the frame 1 and spaced inwardly from the bell-crank lever 18, to the arm 23 of which the handle lever 26 is connected by means of a connecting link 28 secured by a pivot 29 at its inner end to the lever 26 near the pivot pin 27 thereof. It will be observed that the relative positions of the handle 26, link 28 and lever arm 23 are such that when the handle is raised preparatory to operating the tool by a downward movement of said handle the crank portion of said levers (that is, the respective parts between their pivots and the points at which the link 28 is connected) are at that point in the arc of movement whereby a maximum amount of travel will be imparted to the link 28 and of course, the lever arm 23. However, the laterally extending arm 22 of the crank 18 is above its arc of maximum travel so that while there may be a maximum amount of movement imparted to the link 28 by the lever 26 there is a minimum movement imparted by the lever arm 22 to the link 24. Therefore, in a sense, the actuating lever 26 and the force imparting lever 22 may be said to be in opposition. The reason for this is to equalize the amount of movement between the handle 26 and the lever arm 22 so that throughout the greater part of the movement of the handle 26 the amount of movement of the block 17 (or what amounts to the same thing, the amount of movement of the frame 1) will be uniform. This is shown by the dotted position in Fig. 1. The first dotted position is approximately 45° from the full position, and the second dotted position

is approximately 45° from the first dotted position, and while the operating handle 26 is moving through these respective arcs the frame 1 in each instance will move a distance indicated by the dimension x. However, for the last 45° of movement shown in Fig. 2 the point of connection between link 28 and lever 26 passes a dead center and the amount of movement of the frame will be somewhat reduced. This is one of the objects sought to be accomplished by the arrangement of link and lever connections adopted by me, because near the end of the lever arm movement the spring S has already been considerably compressed and the greater amount of leverage is desirable on account of the increased resistance of the spring. During the same amount of movement from the first dotted position shown in Fig. 2 to the second dotted position when the operating lever 26 has reached the end of its travel the pivotal connection 29 passes the center of its rotation (which is the pivot pin 27) and, of course, the lever becomes locked in this position so that it can not accidentally be displaced.

From the foregoing it should be apparent that the arrangement of the actuating parts, including the position of the handle lever 26, when said lever has been moved to its full extent downwardly, greatly facilitates the operation of the tool by the mechanic. For instance, he may hold the frame 1 with his right hand, including in his grip the handle 26, while his left hand is free to remove the lock L which releases the valve V so that it may be lifted out of the block. It should also be apparent that when the lever 26 approaches its lowermost position the stresses on the tool are greatest and the force applied to the handle comes almost directly opposite the lower end of screw 13 (the point of anchorage), reducing to a minimum any torsional strains on the frame 1.

Having described my invention, I claim:

1. In a valve lifter the combination of a handle frame, a guide member disposed transversely at one end of the frame, a valve engaging member slidably mounted in said guide for co-action with the frame, a block adjustably mounted on said valve engaging member, a bell-crank mounted on the frame in close proximity to said guide member, a handle lever pivotally mounted on the frame at a point spaced inwardly from the bell-crank lever, a connecting link between said block and the upper arm of the bell-crank lever, and a second connecting link between the lower arm of the bell-crank lever and the handle lever, the points of connection of the links with the respective levers being such that the first link will move substantially along a vertical line and the second along a horizontal line.

2. In a valve lifter the combination of a handle frame, a guide member disposed transversely at one end of the frame, a valve engaging member slidably mounted in said guide for co-action with the frame, a block adjustably mounted on said valve engaging member, a bell-crank mounted on the frame adjacent to said guide member, a handle lever pivotally mounted on the frame at a point spaced inwardly from the bell-crank lever, a connecting link between said block and the upper arm of the bell-crank lever, and a second connecting link between the lower arm of the bell-crank lever and the handle lever, the points of connection of the links with the respective levers being such that the pivotal point of the first link with the bell-crank lever moves away from dead center when the pivotal point

of the second link and handle lever moves toward dead center.

3. In a valve lifter the combination of a handle frame, a guide member disposed transversely at one end of the frame, a valve engaging member slidably mounted in said guide for co-action with the frame, a block adjustably mounted on said valve engaging member, a bell-crank mounted on the frame adjacent to said guide member, a handlelever pivotally mounted on the frame at a point spaced inwardly from the bell-crank lever, a connecting link between said block and one arm of the bell-crank lever, and a second connecting link between the other arm of the bell-crank lever and the handle lever, the points of connection of the links with the respective levers being positioned so that when the first link operates at approximately 90° from the dead center of its crank, the second connecting link operates across the dead center of the handle lever arm to which it is connected.

4. In a valve lifter the combination of a handle frame, a guide member disposed transversely at one end of the frame, a valve engaging member slidably mounted in said guide for co-action with the frame, a block adjustably mounted on said valve engaging member, a bell-crank mounted on the frame adjacent to said guide member, a handle lever pivotally mounted on the frame at a point spaced inwardly from the bell-crank lever, a connecting link between said block and one arm of the bell-crank lever, and a second connecting link between the other arm of the bell-crank lever and the handle lever, the points of connection of the links with the respective levers being positioned so that when the link between the two levers moves rapidly the link between the bell-crank lever and the block will move slowly.

JOSEPH SUNNEN. 20
